THREAD-ADVANCING REEL

Lorin A. Corey, Cleveland Heights, Ohio, assignor to Industrial Rayon Corporation, Cleveland, Ohio, a corporation of Delaware

Application May 27, 1944, Serial No. 537,557

2 Claims. (Cl. 34—153)

1

The present invention relates to a processing apparatus of the thread-storing, thread-advancing type intended for processing and handling of thread, filaments, bands, ribbons, etc.

More particularly, the invention relates to a cantilever type reel, i. e., a reel supported and driven from one end only with its other end free and unobstructed. Reels of this type are used, for example, in the production of viscose rayon by the continuous process. They function by virtue of an offset and inclined relation between the axes of the members supporting the thread, as shown and described in the Knebusch Patent 2,210,914.

In the continuous process of producing viscose rayon, cantilever reels are advantageously used in the performance of a series of individual processing steps. Drying of the viscose yarn or thread is one of these processes and it is performed by advancing the wet yarn or thread over the periphery of a reel through whose interior a heating fluid is circulated. However, the thread has an inherent tendency to shrink on drying and this tendency sometimes has the effect of springing the reel shaft to destroy the offset and inclined relation between the reel members supporting the thread. It is desirable, therefore, to support the reel members in a manner so as to obviate any change from their original relation.

Cantilever reels used in drying of thread, as well as in other treating processes, are desirably made of a light material having good heat transfer qualities, such as aluminum. Their construction should also provide for a heat transfer area which is the same over the entire reel periphery to provide uniform drying. Also, the circulation of the heating fluid should be substantially constant and effective to provide a continuous and constant transfer of heat.

The present invention provides a drying reel in which a rapid and constant transfer of heat is had. This is done by a means adapted to withdraw the heating fluid substantially immediately after it is cooled. The invention further provides a supporting structure or frame that substantially entirely eliminates the springing of the reel members. Also, the construction of the supporting structure lends itself to easy handling as, for instance, in machining operations and for purposes of replacement of parts.

These and other novel and advantageous features will be apparent from the following description and drawings where:

Figure 1 is a plan view in section of the thread-

2

advancing, thread-storing cantilever type reel employed in the drying of thread or the like;

Figure 2 is an elevation partly in section of the apparatus of Figure 1;

Figure 3 is an enlarged view partly in section of a part of an alternate supporting frame member;

Figure 4 is a view taken on line A—A of a heating fluid withdrawing means employed in the apparatus;

Figure 5 is a modification of Figure 4.

The thread-advancing reel of Figures 1 and 2 comprises two reel members 10 and 11 operating on the principle of the reel shown and described in the Knebusch Patent 2,210,914. The two reel members 10 and 11 are rigid and of substantially circular cross section. Their peripheries are formed of spaced, longitudinally extending bar members 12 and 13, respectively. The bar members 12 of reel member 10 and 13 of reel member 11 are interleaved in interdigitating relation. Reel members 10 and 11 are mounted for rotation about axes which are offset and inclined to each other so as to cause the reel members to advance thread in spaced, generally helical turns from the receiving end of the periphery to the other end.

Spaced, longitudinally extending bar members 13 of reel member 11 also form the periphery of hollow cylinder 14. The cylinder is provided with a front closure member 15 and a rear closure member 16 to form an enclosed chamber 18. Closure members 15 and 16 also serve to support the reel member 11 concentrically on shaft 17 which passes through its interior. Furthermore, by sealing the closure members against the shaft, chamber 18 becomes fluid tight enabling the use of a drying medium as hot water, steam, hot air, etc. The reel being described, however, is generally best suited for use with hot water although it may be utilized with any other suitable heating medium. Also, an electrical heating element can readily be provided within the reel.

Closure members 15 and 16 contain concentric wedge-shaped recesses about shaft 17 adapted to receive wedge-shaped sealing gaskets 20, 21 made of a suitable pliable material such as lead. In the closure member 16, the sealing gasket 21 is additionally backed up by a ring 27 bearing against a shoulder 24 of the shaft 17. Gasket 20 is forced into the recess in closure 15 and maintained therein by means of a cap 22. The cap is drawn into tight relation with the gasket by means of a screw 23 threaded into the front portion of shaft 17. By drawing tightly on the screw 23, the lead-

sealing gaskets frictionally bind reel member 11 to shaft 17 causing the reel to rotate therewith.

Shaft 17 has a hollow core passage 25 and another passage 26 concentric therewith, both extending throughout substantially the entire length of the shaft. The shaft is desirably plugged at the unsupported end for a short distance back. The plug extends into the concentric shaft passage 26 slightly beyond opening 30. Opening 30, near the closure member 15, serves as an inlet for heating fluid to chamber 18. The plugged end of shaft 17 is drilled out and tapped to permit the threading of screw 23 therein.

The rear closure member, as shown in Figures 1 and 4, has an inwardly extending boss 31 concentric with and encompassing shaft 17. Within the boss is an annular recess 32 about the shaft and about the outlet opening 29, joining the shaft passage 26 and the recess. The boss, in turn, has a radial portion 33 extending to substantially the cylinder wall. In this radial portion is a passage 34 joining the opening 29 in shaft 17 and the interior of chamber 18. Thus, heating fluid can be supplied to the chamber 18 through the inlet 30 and withdrawn through the outlet passage 34. If the heating medium is hot water, a single exhaust or outlet passage may prove sufficient since it is continuously immersed in the liquid. The circulation of the hot water will be outwardly to the cylinder wall and rearwardly to the outlet 34.

The heating fluid transfers heat through the aluminum cylinder wall of the chamber to the longitudinal members comprising the reel and to the thread being advanced thereon. Upon yielding heat to the cylinder wall or, shortly thereafter, the liquid is withdrawn at substantially the region of heat yield or transfer, that is, from adjacent the wall of the chamber. The heating fluid is thus not permitted to be chilled to any great extent and, as a result, to create strata of different heat levels within the cylinder. Furthermore, the radial portion 33 does not obstruct any of the cylinder wall to diminish its heat transfer area.

Although in the illustration of Figure 1 the heating fluid entry is shown near the front of the chamber and the outlet near the back of the chamber, the reverse positioning of the inlet and outlet is substantially similarly effective in the circulation of the heating medium.

In Figure 5, the heating fluid withdrawing means may comprise a plurality of passages 34 tangentially extending from the annular recess 32 in the boss to the cylinder wall. This type of construction is preferred when the heating fluid used is steam and condensation occurs in the chamber for there will always be at least one passage immersed in the condensate for effecting its withdrawal. By positioning the passages in a tangential manner, a scooping action is had facilitating the withdrawal of condensate during the rotation of the reel. The withdrawal opening of each passage 34 may be enlarged, if desired, to form a greater scoop. Also, a plurality of outlets will equalize the withdrawal of a heating fluid, such as hot air or gas, creating a more uniform temperature in the chamber.

The tendency to destroy the offset and inclined relation between the reel members due to thread drying is minimized by mounting the supporting portion of the rotatable reel member 10 back of the first frame-supporting bearing. Any deviation of the reel member from its posi-

tion is resisted by that part of the shaft 17 between the frame-supporting bearings.

Referring again to Figure 1, the second reel member 10 whose bar members are interleaved with those of reel member 11 is mounted on an axis that is offset and inclined to the axis of reel member 11. The second reel member, which may be termed the eccentric reel member, is comprised of bar members 12 forming a rigid cagelike construction. The reel member 10 is of generally circular cross section, like reel member 11, and has its longitudinally extending bar members 12 secured at their unsupported ends to the reinforcing ring 35. The supported ends of the reel members merge into a flange 36. Flange 36 is fixed by means of screws 37 at desirable points adjacent its periphery to an eccentrically mounted hub 40. Hub 40 is mounted on antifriction bearings 41, 42 positioned at its ends and themselves mounted on an eccentric sleeve 49 of frame member 47. The axis of the bore of sleeve 49 is offset from and inclined to the axis of shaft 17. The wide spacing of the hub bearings is desirable inasmuch as the hub provides the only support for the eccentric reel member. Furthermore, such wide spacing of the bearings provides a support for the maintenance of the offset and inclined relation between the reel members 10 and 11.

To prevent contact between adjacent bar members of the reel, intermeshing gearlike members 43 and 44 are employed. Gear member 43 is concentrically mounted with respect to the shaft 17 and is held on reel 11 by means of screws 45. Gear member 44, whose teeth intermesh with gear member 43, is affixed by means of screws 46 to the eccentric reel flange 36. Then, because the concentric reel member 11 is frictionally fixed to shaft 17, it serves as a driving means through the gears 43, 44 for the eccentric reel member 10 which is rotatably mounted on sleeve 49 of the supporting frame member 47. There is thus provided by means of the gears a positive driving engagement of the drying reel where the interdigitating members do not contact each other. This type of driving means is shown and described in Patent 2,255,017 issued to G. P. Torrence et al.

Supporting frame member 47 comprises two sections, a yoke section 48 and a sleeve section 49. The two sections may consist of a single casting as shown in Figure 3; however, it is preferred that the sections be separable for machining purposes and assembly. The sleeve portion 49 of the frame member is eccentrically machined to provide the required offset and inclined relation of reel member 10. Sleeve 49 has at one end an antifriction bearing holding ring 52. The ring 52 encloses an antifriction bearing 53, and its sleeve extension is threaded into the eccentric sleeve 49. The other end of sleeve 49 enlarges into a flange 51. Flange 51 is fixed, by means of screws 50, to yoke 48. Bearing 53 is held in position by being forced against a locating ring washer 54 positioned against shoulder 24 of shaft 17. The flange 51 is utilized for the purpose of mounting the entire apparatus as a unit in a machine embodying a plurality of similar units as shown and described in the Torrence et al. Patent 2,217,716.

Yoke member 48 merges at its other end into a ring 55 enclosing an antifriction bearing 56. Bearing 56 is held in place by snap rings positioned on either side of the bearing and in the 75 ring wall, and on the shaft by locating rings 57,

58 also on either side, each locating ring having set screws 59, 60 turned into the shaft. Thus, frame member 47 is mounted on an antifriction bearing 53 at the reel end and an antifriction bearing 56 at the other end. Having bearings at either end of the frame member minimizes the flexing of that portion of shaft 17 projecting beyond the bearing 53, that is, that portion supporting reel member 10. Also, by the provision of bearings in each end of the frame-supporting member 47, which is of substantial length, the widest possible spacing of bearings is had and the danger of destroying the inclined and offset relation of the reel members is substantially entirely eliminated.

To facilitate the supplying of a heating fluid to the reel and its removal therefrom, there is provided a seal housing 62 fixed as by means of screws 61 (see Figure 2) to the flanged portion of the frame 47 bearing holding ring 55. The housing 62 comprises two internal chambers, an inlet chamber 63 and an outlet chamber 64. A sealing gasket 65 is disposed between the housing and the annular rim 70 abutting the flange of ring 55 in order to prevent the escape of heating fluid therebetween. Within the housing 62, a rotatable sealing member 66 is fixed on the shaft by means of a set screw 67. Two carbon rings 68 and 69 forming a part of the sealing member 66 contact the inner faces 70, 71 of annular rims of housing 62. Between each carbon ring and the intermediate downwardly extending wall portion of sealing member 66, which forms an annular channel in the seal housing, is disposed a flexible packing material 72, 73. This material is urged against the shaft, the carbon ring, and the seal member wall by coil springs 74, 75 preventing leakage of the heating fluid.

The inlet chamber 63 is at the rear of the housing 62 and shaft 17 terminates therein. The shaft end has the core conduit 25 open and the annular conduit 26 closed, permitting only the entry of the heating fluid at that point. The exhaust or outlet is through the side of the housing 63 through outlet chamber 64, and through an opening 76 in the channel portion of the sealing member 66 joining the outlet chamber 64 with the concentric shaft passage 26. At the extreme end of the seal housing is a plugged opening 80 utilized for inspection purposes only.

Hot water or other heating fluid is supplied through the inlet chamber 63, shaft core passage 25 to the chamber 18 of reel member 11, and is withdrawn through chamber 18, outlet 34, the annular conduit 26 in shaft 17, and through the seal outlet chamber 64 and exhaust opening 77. In this fashion, a constant flow of drying fluid is maintained.

In either illustration, Figure 1 or Figure 3 of the frame support, a driving gear 78 is mounted on shaft 17 and within the yoke section. The gear is preferably placed adjacent the rear bearing 57 in order that in the event of any radial thrust, such thrust will be taken by the bearing and not the shaft. The drive gear 78 is held securely on the shaft by means of set screws 79.

The herein described embodiments of the invention are, of course, for purposes of illustration

only; therefore, it is intended that the patent shall cover by the appended claims all features of patentable novelty that reside in the invention.

I claim:

1. A thread-storing, thread-advancing reel comprising two interdigitating sets of bar members, each set being mounted for rotation about an axis displaced in an inclined relation to the other, a supporting frame member for said sets of bar members, a shaft journaled in said frame member and projecting therethrough having heating fluid inlet and outlet means, a first reel member comprising a cylindrical chamber having a periphery of spaced, longitudinally extending bar members mounted coaxially with and upon said projecting portion of the shaft including the heating fluid inlet and outlet means, said chamber in said first reel member being adapted to receive and have drawn therefrom a heating fluid through said shaft inlet and outlet means, heating fluid withdrawing means in said chamber joining said shaft fluid outlet means, said heating fluid withdrawing means comprising an inwardly extending hub at one end of said chamber, said hub encompassing a shaft passing through the chamber and having an annular recess in its body portion and around said shaft, said recess joining an outlet means in said shaft, a conduit extending radially from said hub to substantially adjacent the cylindrical wall of the chamber joining said annular recess and the interior of said chamber, and a second reel member comprising a set of spaced longitudinally extending bar members alternately disposed with respect to those of said first reel member rotatably mounted on said supporting frame member.
2. A thread-storing, thread-advancing reel comprising two interdigitating sets of bar members, each set being mounted for rotation about an axis displaced in an inclined relation to the other, a supporting frame member for said sets of bar members, a shaft journaled in said frame member and projecting therethrough having heating fluid inlet and outlet means, a first reel member comprising a cylindrical chamber having a periphery of spaced, longitudinally extending bar members mounted coaxially with and upon said projecting portion of the shaft including the heating fluid inlet and outlet means, said chamber in said first reel member being adapted to receive and have drawn therefrom a heating fluid through said shaft inlet and outlet means, heating fluid withdrawing means in said chamber joining said shaft fluid outlet means, said heating fluid withdrawing means comprising an inwardly extending hub at one end of said chamber and around the shaft passing therethrough, said hub encompassing an outlet means in said shaft, said hub having an annular recess around said shaft and outlet means, a plurality of conduits joining said recess in said hub and extending tangentially to substantially adjacent the wall of said chamber, and a second reel member comprising a set of spaced longitudinally extending bar members alternately disposed with respect to those of said first reel member rotatably mounted on said supporting frame member.

LORIN A. COREY.
